UNITED STATES PATENT OFFICE.

DWIGHT E. REYNOLDS, OF LIVERPOOL, NEW YORK.

CLOTHESRACK.

Application filed August 30, 1923. Serial No. 660,188.

To all whom it may concern:

Be it known that I, DWIGHT E. REYNOLDS, a citizen of the United States of America, of Liverpool, in the county of 5 Onondaga, in the State of New York, have invented new and useful Improvements in Clothesracks, of which the following, taken in connection with the accompanying drawings, is a full, clear, and exact description.

10 This invention relates to certain new and useful improvements in clothes racks.

The main object of the invention is the production of a simple, durable and comparatively inexpensive construction of 15 clothes rack in which the clothes supporting arms are adjustable to various heights from the ground to provide an unobstructed passage thereunder, the construction of such arms and their supporting means being further, of such a character as to permit the 20 collapsing of the arms into a compact structure combined with stop means for preventing their collapsing movement beyond predetermined points.

25 Another object relates to the particular structure of the mechanism for raising and lowering the arms and for maintaining such mechanism in proper adjustment.

Other objects and advantages relate to 30 the details of the structure, all as will more fully appear from the following description taken in connection with the accompanying drawings in which:

Figure 1 is a top plan view of the clothes 35 rack.

Figure 2 is an elevation of the gearing and its associated parts.

Figure 3 is a section on line 3—3, Figure 1.

40 Figure 4 is a section on line 4—4, Figure 2.

Figure 5 is a section on line 5—5, Figure 2.

The clothes rack here illustrated 45 comprises an extensible post or standard —1— formed as shown, of two sections, an outer section —2— of tubular form adapted to extend some distance into the ground or as illustrated, into a hollow cement base —3— 50 provided for the purpose.

Within the tubular section —2— is telescopically mounted, an inner tubular section —4— of a diameter to freely slide within the section —2—.

55 The inner section —4— carries near its upper end, a casting —5— consisting of a

hub —6— and a series of, in this instance, five radiating channel bars —7—.

Each channel bar is adapted to receive within its channel a radiating arm —8— 60 which may be of wood or other suitable material adapted to carry or have threaded through it, the rope or ropes or other suitable line —9— constituting the clothes carrying part.

The casting —5— is of peculiar construction in that each of the channel bars —7— consists of two substantially parallel radiating side members —10— unconnected for the main portion of their length, each integrally connected to the hub —6— and at their outer ends, connected by an integral cross bar —11— upon which cross bar, the arms —8— are adapted to rest when positioned in the channel bars —7— and secured to the respective channel bars by means of bolts —12— extending through the opposite side members of the respective channel bars and through the respective arms —8— for pivotally connecting 80 the arms —8— to the channel bars and permitting upward swinging of the arms —8—, while the cross bars —11— limit the downward pivotal movement of said arms.

For the purpose of holding the arms —8— 85 in proper relation with respect to the post —1— and the channel bars —8—, a screw —13— is provided having an enlarged flattened circular head —14— adapted to pass between the side members —10— when 90 the head is turned into a position substantially parallel with the side members —10— and then to be turned to a position at substantially right angles to the side members —10— whereupon the head —14— engages 95 the side members to prevent upward pivotal movement of the arms —8— to their collapsed position.

Further, the said members —10— are connected by an integral downwardly extending 100 cross flange or wall —15— having its rear face of considerable extent and substantially plain so that when the arms —8— are collapsed upwardly, the flat rear portion of the lower surface of the arms come in contact 105 with the flat inner face of the respective flanges —15— to limit the collapsing movement of the arms —8—, and preferably, this stop acts at a point where the arms extend upwardly and incline slightly inwardly from 110 the vertical so as to normally maintain themselves in that position.

The casting —5— is preferably slidably mounted on the upper end of the inner section —4— and its downward movement is limited by a ring member —16— mounted on the inner section —4— and secured thereto by a transverse pin or bolt —87—.

This ring member —16— likewise forms a limiting stop which determines the downward telescopic movement of section —4— with the section —2—, and the ring may be provided with a circular recess adapted to receive the upper end of the outer section —2— to more effectively assure a tight joint preventing the entering of water within the section —2—, and the inner section —4— may be provided with a cap —17— of any suitable form for preventing the entry of water to the inner section —4—.

For the purpose of raising and lowering the inner section —4— with respect to the outer section —2—, there is provided a suitable manually-operated gearing consisting of a relatively small gear —17— pinned to a shaft —18— journaled in a pair of brackets —19— and —20— which brackets are clamped about the outer section —2— by means of bolts —21—, —22—, and —23—, the shaft —18— being positioned between the bolts —22— and —23— and having at one end, a crank arm or handle —24— mounted upon it for rotating the gear.

Preferably, some means is provided for holding the gear —17— in any position of adjustment and for this purpose, I have shown the dog —25— rotatably mounted upon the bolt —23— and adapted to engage any one of the recesses —26— in the gear —17—.

A second gear —27— is provided having plugs or teeth —28— meshing with and fitting with the recesses —26— in the gear —17—, and the outer section —2— is formed with a slot —29— alined with the gear —27— and through which the gear —27— projects so that its teeth —28— engage with series of openings or perforations extending through and arranged longitudinally of the inner section —4— so that by rotating the gear —27—, the section —4— will be raised or lowered by reason of the fact that its teeth —28— seat in the openings or perforations —30— in the section —4— and move the latter up or down as the gear is rotated in one direction or the other.

The gear —27— is mounted on a shaft —31— journaled in yokes —36— and —37— slidably carried by brackets —32— and —33— respectively, said yokes being clamped about the outer section —2— by means of bolts —34—, —35— and —36— and for the

purpose of adjusting and maintaining the gear —27— in its preferred position of adjustment.

The yokes —36— and —37— are formed at their forward ends with slots —38— and —39— through which bolts —40— and —41— extend, said bolts being secured to the brackets —32— and —33—, and the brackets are formed with flanges —42— through which set screws —43— extend, and have their forward ends in engagement with the brackets —36— and —37— respectively to move the said yokes forwardly or rearwardly with respect to the brackets to properly adjust the gear —27— with respect to the inner section —4— of the post —1—.

Further, in order to maintain the gears —17— and —27— in proper relative position, the bracket —20— is formed with a lug —44— through which the bolt —45— extends for threaded engagement with the lug —46— upon the bracket —33—, whereby the gears may be held from separation or spreading apart under the strain exerted upon them in elevating the inner section —4—.

Although I have shown and described a specific construction as illustrative of a preferred embodiment of my invention, I do not desire to limit myself to the details of form, construction or arrangement, as various changes may be made within the scope of the appended claim.

I claim:

A clothes-rack comprising a post, a casting having a hub mounted upon the post, and a plurality of channel bars radiating from the hub, each of said channel-bars comprising spaced substantially parallel side members and an open bottom except for a pair of spaced cross-members connecting said side members, the inner one of said cross-members having a flat substantially vertically disposed surface, an arm mounted in the channel of each of said radiating bars and adapted to rest upon its respective spaced cross-members at one of its limits of movements and adapted to contact with the flat vertical surface of the inner cross-bar at its other limit of movement, means for pivotally connecting each arm to its respective channel-bar each bar being provided with a rotatable member movable through the open bottom of its channel bar and between the cross-members and adapted to be turned to a position to lock its arm to the respective channel-bar.

In witness whereof I have hereunto set my hand this 16th day of August 1923.

DWIGHT E. REYNOLDS.
